DESIGN FOR A RIBBED METAL EAVES TROUGH

Louis Kuehn, Milwaukee, Wis., assignor to Milcor
Steel Company, Milwaukee, Wis., a corporation
of Delaware

Application January 4, 1937, Serial No. 66,882

Term of patent 14 years

To all whom it may concern:

Be it known that I, Louis Kuehn, a citizen of the United States, residing at Milwaukee, county of Milwaukee, State of Wisconsin, whose post office address is 3432 North Lake Drive, Milwaukee, Wisconsin, have invented a new, original, and ornamental Design for a Ribbed Metal Eaves Trough, of which the following is a specification, reference being had to the accompanying drawing, forming a part thereof.

In the drawing:

Figure 1 is a rear side view of the eaves trough showing my new design.

Figure 2 is a top view of the same.

Figure 3 is a front side view of the same.

Figure 4 is an end view of the same, viewed from the right of Fig. 3.

Figure 5 is a perspective view of the same, viewed from a point above and to the left.

My invention is characterized by an eaves trough of the configuration shown having a relatively wide rib in each of the sides and in the bottom thereof longitudinally extended but stopped short of either end of the trough.

I claim:

The ornamental design for a ribbed metal eaves trough, as shown and described.

LOUIS KUEHN.
